UNITED STATES PATENT OFFICE.

ANDREW LINDSTROM, OF SAN FRANCISCO, CALIFORNIA.

BELL-BUOY.

1,072,130.

Specification of Letters Patent.

Patented Sept. 2, 1913.

Application filed January 29, 1912. Serial No. 674,093.

To all whom it may concern:

Be it known that I, ANDREW LINDSTROM, citizen of the United States, residing at San Francisco, in the county of San Francisco and State of California, have invented 5 certain new and useful Improvements in Bell-Buoys, of which the following is a specification.

My invention relates to bell buoys, and 10 particularly to that special class of buoys wherein the bell or other sounding mechanism is operated by a float disposed within the buoy, the float being actuated by the rise and fall of the waves.

15 One object of my invention is the provision of a buoy particularly adapted to sound both a submerged and a surface signal.

A further object is to provide a buoy with 20 submerged and surface signal bells and oppositely disposed hammers operated by the rise and fall of a float located within the buoy.

A further object is to provide a buoy of 25 such contour that its rise or fall will be retarded relatively to the rise and fall of the waves, so that the internal float shall secure a maximum of movement.

A further object is to provide means 30 whereby the hammers operating upon the bells shall be positively actuated by the rise and fall of the float, and whereby the hammers shall normally be held in a position away from the bell, but may be tripped by the actuation of the float to cause a signal 35 to be struck upon the co-acting bell.

Still another object is to provide a very 40 simple and effective form of buoy of this character having a minimum of parts and being so situated that the bell sounding mechanism may be easily repaired or readjusted when desired.

Other objects will be apparent in the course of the following description.

My invention is illustrated in the accompanying drawings, wherein:

Figure 1 is a longitudinal sectional view 50 of my improved bell buoy; Fig. 2 is a cross sectional view on the line 2—2 of Fig. 1; Fig. 3 is an enlarged detail transverse section on the line 3—3 of Fig. 1. Fig. 4 is an enlarged sectional view of the lower end of the buoy shown in Fig. 1, the section being taken in the same plane as in Fig. 1; Fig. 5 is a perspective detail view of the lower 55 cage; Fig. 6 is a side elevation, partly sectional, of one of the hammers and its co-act-

ing tail member; Fig. 7 is a perspective view of the spring for holding the hammers out of contact with the bell.

Referring to these figures, 2 designates 60 the body of the buoy, which is made preferably of sheet metal and which has the form of an elongated ovoid. In other words, while the buoy body tapers toward its ends, it is largest toward the lowest portion there- 65 of. The buoy body is open at its opposite ends, and passing through the body is a tube 3 which is also open at its ends. Extending longitudinally along the inner surface of the tube 3 are a plurality of tracks 4 whose spe- 70 cific construction will be later described.

The upper and lower ends of the tube 3 are connected to the upper and lower ends of the buoy body 2 by means of rivets, bolts or in any other suitable or desired way, and mounted upon the upper and lower ends of the body are the bell cages 5 and 6. These are substantially alike in form, and each cage consists of a central portion having radiating curved arms which are riveted to the adjacent end of the buoy body. The cage 5 is perforated at its center, and passing through it is a headed bolt 7 which passes through the bell 8. Nuts engage the bolt 7 and hold the bolt and the bell in proper relation to the cage. The cage 6 has at its center a downwardly projecting eye 9, within which is disposed a bushing 10. Through this bushing passes the shackle of an anchor chain. This bushing prevents the 80 material of the cage from being worn away by the action of the anchor chain, the bushing being renewable whenever desired. Disposed at the center of the inside face of the cage 6 is a stud bolt 11 upon which is 85 mounted a bell 12, the stud bolt passing through the center of the bell and being screw-threaded for engagement with the nuts 13. The bell is held separate from the cage by means of an annular head 14 formed 90 upon the bolt 11.

Disposed within the tube 3 and traveling vertically upon the tracks 4 is a cylindrical float 15 which is preferably formed of sheet metal. This float is guided upon the tracks 105 4 by means of rollers 16 which are mounted upon the float and project laterally beyond the circumference thereof and engage the tracks 4. Disposed in the upper and lower ends of the tube 3 are pulleys 17 and 18, both 110 having practically the same construction and over which a cable or flexible connection

19 passes. At one end, this flexible connection is connected to the float 15 by means of a spring 20 and an eye 21 riveted or otherwise attached to the upper end of the float 15, while at its other end the cable 19 is connected to a rod 22 which is rigidly attached by means of flanges 23 to the bottom of the float and depends therefrom, the lower end of the rod being formed with an eye to which the cable 19 is attached. The spring 20 tends to keep the cable 19 at all times taut, so that the cable will at all times frictionally engage the pulleys 17 and 18 and rotate the same in one or the other direction as the float 15 rises or falls.

15 Each of the pulleys 17 and 18 is designed to operate a hammer striking mechanism, the pulley 17 operating the hammer striking mechanism for the bell 8 while the pulley 18 operates the striking mechanism for the bell 12.

Generally speaking, each of the pulleys 17 and 18 is provided with laterally projecting pins which engage with the tail of a spring actuated hammer which is normally held from contact with the bell, but which when struck by a pin upon the corresponding pulley is retracted until released, whereupon it springs into contact with the bell and rings it. In detail, the preferable construction is as follows: The pulley 17 is mounted upon a cross bar 24 attached to the tube 3 in any suitable manner. A pivot bolt 25 passes through the cross bar 24 and upon this bolt the pulley 17 is mounted, the pulley being held upon the bolt by means of a cotter pin 26, or in any other suitable manner. Also passing through the bar 24 is a pin 27 which forms the bearing for a pair of hammers 28 and 29, each hammer at its upper end being cleft or bifurcated as to 30 to receive between the parts an angular member 31. The pin 27 passes through the bifurcated ends of the hammers 28 and 29 and also through the members 31. Each member 31 has an inwardly projecting tail 32 and also a nose 33 extending down over the outer face of the corresponding hammer. A spring 34 is mounted within the bifurcated end of the hammer and projects upwardly and inwardly against the face of the tail 32, so that the noses 33 are normally forced against the face of the hammer. It will be seen that with this construction, when the tail 32 is moved in one direction the hammer will be moved with the tail, but when the tail 32 is moved in the opposite direction it will move independently of the hammer. Coiled springs 35^a are connected 60 at one end to each hammer, while at its opposite end each spring is connected to the adjacent portion of the tube 3, or any other suitable support. This coiled spring when expanded and released will act to throw the hammer against the corresponding bell. In

order to hold each hammer in a normal position out of contact with the bell, I provide for each pair of hammers a spring 35. This spring, as illustrated, is in the form of a leaf spring, one end of which is supported by means of the bolt holding the bell in place, the other end extending into engagement with the corresponding pair of hammers 28 and 29. Preferably, this spring 35, as illustrated in Fig. 7, is enlarged at its free end so as to form a loop 36 adapted to receive and surround the heads of both hammers, the hammers being kept separate from each other by means of a rearwardly extending plate 37 attached to the free extremity 70 of the spring and extending at right angles to the face of the spring. This plate 37 is co-extensive with the stroke of the hammers, thus preventing any contact of the hammers with each other and therefore any blocking 75 of the action of the hammers. 80

As will be seen from Fig. 2, the pulley wheel (either 17 or 18) which actuates the pairs of hammers, is disposed between each pair of hammers, and carries upon it alternately spaced, oppositely projecting actuating pins 38 and 39. The pins 38 project on the one side of the wheel, while the pins 39 project on the other side of the wheel and are set alternately to the pins 38. Thus, 90 when the wheel is rotated in the proper direction, the pin 38 will engage the hammer 28, while the pin 39 will engage the hammer 29, or rather, these pins will engage 95 the members 31 whereby the hammers are 100 actuated.

The operation of this buoy will be obvious.

Upon a rise of the float 15 relative to the body of the buoy, the pulley wheels 17 and 18 will be actuated and the pins on the pulley wheel 18 will strike the members 31 and will cause the hammers 28 and 29 at the lower end of the buoy to be alternately retracted and alternately released. It will be seen that the hammers at the upper end 105 of the buoy are reversely set to the hammers at the lower end of the buoy, and as a consequence when the float rises the pins upon the pulley wheel 17 will simply act to 110 oscillate the members 31, which will not 115 affect the corresponding hammers. Thus, the surface signal will not sound, but upon a downward movement of the float the movement of the pulley wheels 17 and 18 will be reversed, and as a consequence the 120 pins upon the wheel 17 will positively actuate the hammers co-acting with the bell 8, while the hammers co-acting with the bell 12 will not be operated.

While I do not desire to be limited to any 125 special form of the tracks 4, I preferably provide two oppositely disposed U-shaped tracks and two oppositely disposed flat tracks, and also preferably provide these tracks with stops 40, at the upper and lower 130

ends, designed to limit the upward and downward movement of the float 15. The upper end of the tube 3 is protected by means of a covering plate 41. This plate 5 extends across the upper end of the tube 3, but is, of course, to be slotted to accommodate the shanks of the hammers and to permit the movement of the hammers. These slots, of course, permit air to pass out

10 of the upper end of the tube 3, but the covering 41 prevents any large quantity of water passing down through the tube and falling upon the float 15, as would occur where a wave would break over the buoy.

15 While my improved buoy will operate to a degree with only one bell hammer or clapper at each end, it is far preferable to have at each end a pair of clappers and set the pins 38 and 39 alternately on opposite sides 20 of the actuating wheels, as thereby the distance between the pins may be decreased so that when one pin is on the point of engaging the trip or tail of one hammer, the next succeeding pin is on the point of engaging the 25 trip or tail of the other hammer. There is thus very little lost motion between the tripping pins on the wheels 17 and 18 and the hammers. The pins 38 and 39 are so spaced from each other that the rise or fall of the 30 float through about three inches would cause at least one actuation of one of the hammers. As the normal rise and fall of the float will be about six inches, it will be seen that there will be at least one actuation of 35 each hammer during a normal reciprocation of the float.

Attention may here be called to the fact that by reason of the peculiar form of the float body 2 the buoy itself has a relatively 40 small lifting power. Thus, as a wave reaches the buoy, the buoy does not immediately rise, but remains relatively stationary, so that the water rises inside of the buoy body, raising the float with it. When 45 the wave recedes, the buoy does not immediately drop, but the water inside drops, causing the float to sink upon itself under weight.

50 My improved buoy is simple in construction, easily repaired, and is positive in its action. It will be seen that when a high sea is running, the area of movement of the float 15 will be relatively large, and that in this case a number of rapid strokes will be 55 sounded upon both the submerged and the surface signal bells. Even where the sea is not high, however, and the waves are normal, there will be a constant sounding of the bell, which is not the case with bell 60 buoys in which the signal bells are sounded by the rocking of the buoy.

65 It will also be noted that not only are the bells sounded upon a rise and fall of the float 15 but that the hammers being free to move will be impelled against the bells by

any lateral or rocking movement of the buoy. The hammers are so supported away from the bell by means of the springs 35 that when the buoy rocks in one direction the hammers will be thrown out against the 70 retractive force of the springs 35, and when the buoy rocks in the other direction the hammers will be thrown inward against the bells.

75 It will, of course, be understood that many minor modifications may be made in the construction without departing from the spirit of the invention.

If desired, the submarine bell can be disposed deeper under water by making the 80 tube 3 extend downward to a greater extent as shown in dotted lines Fig. 1.

Having thus described my invention, what is claimed is:

1. A bell buoy, including a hollow buoyant body open at opposite ends, signal bells carried at opposite ends, a float disposed within the body and vertically movable independently thereof, oppositely disposed pulleys mounted in the said body, a flexible 85 connection passing over said pulleys, mechanism actuated by the rotation of one of said pulleys in one direction to ring the adjacent bell and mechanism actuated by the rotation of the other pulley in the opposite direction to ring the other of said bells. 90

95 2. A bell buoy, including a hollow buoyant body open at opposite ends, a tube extending through the body, signal bells carried at opposite ends of the tube, a float disposed within and guided by said tube, said float being vertically movable independently of the body, pulley wheels disposed at opposite ends of the tube and having laterally projecting pins upon their circumferential margins, and means for transmitting motion of the float to said wheels, bell hammers located at opposite ends of the hollow body, and tripping devices adapted to be actuated by the pins to release said hammers. 100

105 3. In a bell buoy, a shell open at both ends, a vertically movable float disposed within said shell, upper and lower wheels having projections, a flexible connection passing over said wheels and engaging said float, upper and lower bells, and upper and lower hammers operatively engaged by said wheels upon a movement of the float in either direction. 110

115 4. In a bell buoy, a shell open at both ends, a float disposed within the shell, upper and lower wheels having projections, a flexible connection passing over said wheels and attached to said float, upper and lower bells, upper and lower hammers for striking the 120 said bells, and devices whereby a movement of the wheels in one direction will cause the projections on the wheel at one end of the buoy to operatively engage its corresponding hammer and the projection on the other 125 130

wheel to pass its corresponding hammer without actuating the same, and whereby upon a downward movement of the float the hammer at the other end of the float will be actuated in a like manner.

5. In a bell buoy, a shell open at both ends, cages attached to said shell at opposite ends, a bell mounted in each cage, a vertically movable float disposed within the 10 buoy, upper and lower wheels mounted within the buoy and having projections, a flexible connection passing over said wheels and connected to the float whereby the wheels may be rotated in one or the other direction 15 as the float rises or falls, and hammers mounted in proximity to the bells and adapted to be operatively engaged by the projections on the wheels whereby the hammers may be actuated.
20. 6. In a bell buoy, a shell open at both ends, a float disposed within the shell, oppositely disposed wheels, a flexible connection passing over said wheels and connecting with the float whereby the wheels may be 25 rotated in one or the other direction as the float rises or falls, oppositely disposed studs

projecting from each of said wheels, a pair of hammers pivotally mounted adjacent to each wheel, bells with which said hammers engage, and members, one for each hammer, pivoted upon the pivotal axes of the hammers, each of said members having an arm extending approximately parallel to the hammer shank and engaging therewith for movement in one direction and prohibiting the hammer from movement in the other direction, the other arm of each of said members extending out at approximately right angles to the hammer shank and engaged by said studs, the hammers and the operating members connecting therewith being disposed one on each side of said wheel, and the studs on one side of the wheel being disposed in staggered relation to the studs upon the opposite side of the wheel.

45
In testimony whereof, I affix my signature in presence of two witnesses.
